The ornamental design for a bottle, as shown and described.

DESCRIPTION

FIG. 1 is a top view of a bottle, embodying my new design; FIG. 2 is a front elevational view thereof, the back elevational view being a mirror image thereof; FIG. 3 is a left side elevational view thereof; FIG. 4 is a right side elevational view thereof; FIG. 5 is a bottom view thereof; and, FIG. 6 is a perspective view thereof.

The broken line showing of a bottle finish outline is for illustrative purposes only and forms no part of the claimed design.
